United States Patent Office.

WILLIAM H. MORRIS, OF COLD SPRING, NEW YORK.

Letters Patent No. 67,065, dated July 23, 1867.

IMPROVEMENT IN CARTRIDGE-BOXES.

The Schedule referred to in these Letters Patent and making part of the same.

TO ALL WHOM IT MAY CONCERN:

Be it known that I, WILLIAM H. MORRIS, of Cold Spring, in the county of Putnam, and State of New York, have invented a new and Improved Cartridge-Box; and I do hereby declare that the following is a full, clear, and exact description thereof, which will enable others skilled in the art to make and use the same, reference being had to the accompanying drawings, forming part of this specification.

This invention consists in constructing a cartridge-box with a series of blocks or cartridge-receivers constructed and arranged in such a manner that a greater number of cartridges than usual may be contained in a case of a given size, and the cartridges extracted from the blocks or receivers with the greatest facility. In the accompanying sheet of drawings—

Figure 1 is an outer or face view of my invention with the flaps raised in order to exhibit the interior of the case.

Figure 2, a transverse vertical section of the same taken in the line *xx*, fig. 1.

Similar letters of reference indicate like parts.

A represents the case of the cartridge-box, which may be constructed of sheet metal or leather, the latter being the preferable material. The case may be of the usual form, provided with two flaps *a b*, the outer one, *b*, extending down over the entire surface of the outer or face side of the box, and secured at its lower end to the bottom of the case by a strap, *c*, and button, *d*, or other suitable fastening, (see fig. 2.) Within this case *A* there are placed two or more blocks, *B B*, which have each two or more rows of holes made in them to receive the cartridges *C*. In the drawings two blocks *B B* are shown, and two rows of holes in each block. The upper surfaces of the blocks *B B* have each two different surfaces, *ff'*, the former surface, *f*, being higher than the latter, *f'*, as shown more particularly in fig. 2. These two different surfaces are formed by rebating longitudinally the upper surfaces of the blocks, the two surfaces being of equal width, and a row of holes being bored in each surface of each block, the holes of one row being in line with the centres of the spaces between the holes of the other row. The blocks *B B* are connected at their ends by hinges, *D D*, composed each of two metallic plates, *g g*, secured by screws or otherwise to the ends of the blocks, and connected by a rivet, *h*, near their adjoining ends and outer edges. These hinges admit of the upper block *B* being turned outward, as shown in red in fig. 2, when the flaps *a b* of the case are raised, but do not admit of the upper block being turned back beyond a vertical or upright position in the case *A*, as the bottom of the upper block strikes and rests upon the upper edges of the plates *g g*, which are secured to the ends of the lower block. The bottom of the upper block *B* is rebated similar to its upper surface, so that one portion *i* will be lower than the other portion *i'*. This is necessary in order that the bottom of the upper block when in an upright position may bear upon the ends of both rows of cartridges in the block underneath, as will be seen by referring to fig. 2, it being understood that the holes of both rows in the blocks are of equal depth measured from the surface in which each row is bored, and consequently the cartridges in the holes bored in the more elevated surface will project above those in the holes bored in the lower surface. The object of having the two or more rows of cartridges in each block at different heights is to render the cartridges accessible, so that each one may be withdrawn from its hole with the greatest facility, and the object in having the two blocks connected by hinges, as shown, is to admit of the upper block, when exhausted of cartridges, being turned outward so that the cartridges in the lower block will be accessible. Any number of blocks *B* may be employed, with two or more rows of cartridges in each.

What I claim as new, and desire to secure by Letters Patent, is—

1. The employment or use in a cartridge-box of two or more blocks *B*, provided each with one or more rows of holes to receive the cartridges, and connected together by hinges or joints, substantially as and for the purpose set forth.
2. Having the upper and lower surfaces, either or both, of the blocks, rebated or ground longitudinally so as to form planes of different heights, one for each row of cartridge holes, to admit of the ready withdrawal of the cartridges from the blocks, substantially as shown and described.

The above specification of my invention signed by me this 23d day of January, 1867.

WM. H. MORRIS.
